CLAIM

The ornamental design for an earring tool, as shown and described.

DESCRIPTION

FIG. 1 is an environmental perspective view of an earring tool showing my new design;

FIG. 2 is a front elevational view with the rear elevational view being a mirror image thereof;

FIG. 3 is a right side elevational view with the left side elevational view being a mirror image thereof;

FIG. 4 is a top plan view thereof; and,

FIG. 5 is a bottom plan view thereof.

The broken line showing of the human figure in FIG. 1 is for illustrative purposes only and forms no part of the claimed design.
